UNITED STATES PATENT OFFICE.

WILLIAM F. REDDING, OF TROY, NEW YORK.

IMPROVEMENT IN STOP-GAGES FOR WEATHER-BOARDING.

Specification forming part of Letters Patent No. 41,783, dated March 31, 1864.

To all whom it may concern:

Be it known that I, W. F. REDDING, of Troy, in the county of Rensselaer and State of New York, have invented a new and Improved Stop-Gage for Weather-Boarding; and I do hereby declare that the following is a full, clear, and exact description of the same, reference being had to the accompanying drawings, making a part of this specification, in which—

Figure 1 represents a side elevation of my invention, showing its application to clapboarding. Fig. 2 is a plan or top view of the same. Fig. 3 is a front elevation of the same. Fig. 4 is a horizontal section of the same.

Similar letters of reference in the several views indicate corresponding parts.

This invention is intended as an improvement on a stop-gage for weather-boarding, &c., on which a patent was granted to W. E. Stoddard, May 17, 1859.

The invention consists in the employment or use of a slotted bar, to form the guide for the grooved slide, in such a manner that when, by some accident, the screw which is intended to hold the slide in its place works loose while the gage is in use on a building, said slide is prevented from dropping down to the ground, and the workman is enabled to put it back to its place, and refasten it, without the necessity of leaving his work and going all the way down to the ground to pick it up; and, furthermore, the bar becomes so much lighter and cheaper in manufacture.

To enable those skilled in the art to make and use my invention, I will proceed to describe it.

A represents a bar, made of cast or malleable iron or other suitable material, and provided with a handle, B, projecting from its top edge at right angles, as clearly shown in Fig. 1 of the drawings. The upper or outer surface of said handle is dovetailed and fitted to receive the blade C, the point of which forms the fixed point of the gage. The blade C is secured by means of a screw, a, and several holes are provided in the handle B to receive this screw, so that the blade can be moved in

and out and set to project more or less beyond the front edge or face of the bar A, or so that it can be taken off and sharpened, or, when its point breaks, provided with a new point, and replaced and used up near to its very end. If the blade is firmly secured to the handle B, and its point breaks, the whole blade has to be thrown away, and it is difficult and expensive to take it off and replace it by a new one.

The bar A forms the guide for the slide D, which forms the movable part of the gage. By referring to Fig. 2 of the drawings, it will be noticed the bar A is provided with a slot, b, to receive a central projection of the slide, which is provided with grooves d to catch over the edges of the bar on the sides of the slot b. The slot b extends down nearly to the end of the bar, leaving said end solid, so that when, by some accident, the screw e, which secures the slide in its place should work loose while the gage is in use on a building, said slide is prevented from dropping down to the ground, and the workman is enabled to replace it without loss of time. Furthermore, by making the bar slotted the entire gage becomes lighter and more convenient to handle, and it can be made cheaper on account of the saving in stock.

In using my gage I set the slide to the width of the uncovered portion of the boards to be secured, place the same at the bottom edge of the first board nailed to the building, and drive the spur into the wood by striking the handle. The second board is then placed on the top of the bar A and fastened, and so on, as shown in Fig. 1 of the drawings.

Disclaiming all and everything which is claimed and described in the Letters Patent of W. E. Stoddard, what I claim as new, and desire to secure by Letters Patent, is—

The use of the slotted bar A, provided with an adjustable blade, C, in combination with the slide D and set-screw e, as and for the purpose set forth.

WILLIAM F. REDDING.
